US0D1060375S

(12) **United States Design Patent** (10) Patent No.: **US D1,060,375 S**
(45) Date of Patent: ** Feb. 4, 2025

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Hyunwoo Yoo**, Suwon-si (KR); **Taehyun Kang**, Suwon-si (KR); **Kyungdae Park**, Suwon-si (KR); **Jungsun Jin**, Suwon-si (KR); **Wonje Lee**, Suwon-si (KR)

(73) Assignee: **SAMSUNG ELECTRONICS CO., LTD.**, Suwon-si (KR)

(**) Term: **15 Years**

(21) Appl. No.: **29/778,446**

(22) Filed: **Apr. 13, 2021**

(30) **Foreign Application Priority Data**

CLAIM

The ornamental design for a display screen or portion thereof with graphical user interface, as shown and described.

DESCRIPTION

FIG. 1 is a front view of a display screen or portion thereof with graphical user interface showing our new design; and, FIG. 2 is an enlarged view of the claimed portion of FIG. 1, shown separately for clarity of illustration.

The outer perimeter shown in broken lines in FIG. 1 illustrates a display screen or portion thereof and forms no part of the claimed design.

1 Claim, 2 Drawing Sheets
